MICHAEL DIORENZO, OF IRONDALE, WASHINGTON.

FARM-GATE.

1,076,960.

Specification of Letters Patent.

Patented Oct. 28, 1913.

Application filed December 16, 1912. Serial No. 736,944.

To all whom it may concern:

Be it known that I, MICHAEL DIORENZO, a citizen of the United States, residing at Irondale, in the county of Jefferson and State of Washington, have invented certain new and useful Improvements in Farm-Gates, of which the following is a specification.

This invention relates to that class of gates which may be opened or closed by passengers in carriages without descending from their vehicle.

The object of my invention is the provision of improved devices of the class described of simple construction for actuating a gate.

The invention consists in the novel construction of gate actuating mechanism and in the adaptation and combination therewith of unlatching devices, as will be fully described in the following specification, illustrated in the accompanying drawings, and finally set forth in the appended claims.

In said drawings, Figure 1 is a view in side elevation of a gate and gate actuating apparatus embodying my invention. Fig. 2 is a plan view of the gate actuating mechanism. Fig. 3 is a vertical sectional view through 3—3 of Fig. 2. Fig. 4 is a detached perspective view of a detail of the invention. Fig. 5 is a detached plan view of the locking bolt, one of the elements of the invention.

Referring to said drawings, and particularly to Fig. 1, the reference numeral 1 indicates the main gate post of a gate-way, and 2 a swinging gate of suitable construction operatively connected thereto by brackets 3 and 4. The vertical end bar 5 of the gate is provided with a pivotal pin 6 at its lower end mounted in a bracket 4 and at its opposite upper end arranged with a rigidly secured pyramidal metal cap 7 preferably fitting over the fashioned upper extremity of said bar. At its apex said cap is formed with a circular bearing 8 pivotally engaged in a collar 9 extending downwardly from said bracket 3. Said cap is further formed with a squared extension 10 upon which is rigidly mounted a bevel-gear pinion 11.

Rigidly mounted in said bracket 3 is a horizontal shaft 12. Rotatably mounted in opposing spaced relation on said shaft are a pair of bevel-gear elements 13 and 14, respectively, (see Fig. 4) in continuous mesh upon opposite sides of said bevel-pinion. Each of said bevel-gears is formed integrally or otherwise rigidly provided with a segmental wing 15 formed at one end with an arcuate slot 16 adjacent its circumferential edge. In the same relative position at its other lower end each wing is provided with a cam-block 17 protruding from the plane surface 15¹ toward the similar surface of the respective opposing wing. Said cam-block of each said wing comprises a concave inclined face 17¹ increasing in height toward said lower end of the respective wing. As has been stated, said bevel-gears are in continuous mesh upon opposite sides of the bevel-pinion 11 with the result that they oscillate in opposite directions upon the turning of the gate and resultant oscillation of the bevel-pinion; and conversely, said gate is actuated through the alternate operative connection of the respective wings of said bevel-gears with actuating devices which will now be described. Loosely pivoted at one end to said shaft 12 is a lever 18 pivotally connected at its opposite end to a link 19 whose upper end is in turn pivotally connected at one extremity of a power-lever 20 which is fulcrumed intermediate its ends, as at 21, in said post 1 and provided with a weight 22 adapted to be adjustably positioned along the length of the lever. Numerals 23 and 24 represent cords severally attached to said weight or power-lever and running through a block 25 secured to the top of said post, extend respectively in diverse directions and arranged with their opposite ends, not shown, within convenient reach of the wayfarers on horseback or in vehicles and at a distance from the gate. A vibratile bolt 26 (see Fig. 5) is housed in a chambered extension 27 formed upon said lever 18. Said bolt is substantially triangular in configuration and pivotally mounted at 28 centrally of the extension chamber and having its bolt ends 29 and 29¹ respec-

tively protruding from the opposite open ends of said chamber, and positioned relative to the common axis 12 of said wings and lever 18 to engage in said slots 16 and be effected by said cam-blocks 17. Said bolt is thus arranged to be vibrated from one side to the other upon the pivotal pin at 28 and is formed with abutments 30 upon each of said bolt-ends to engage with the respective wall and limit the amount of projection of the opposite bolt end.

To open or close a swinging gate to its fullest extent requires a movement on its pivotal supports of approximately ninety degrees or one-quarter of a circle. Such movement is effected through the bevel-pinion by actuation of one or the other of said bevel-gears through operative connection of their respective wings 15 with said lever 18 through the bolt 26. When said gate is in its normal open or shut condition, said wings are positioned respectively at the two opposite extremities of their travel, as shown in full lines in Fig. 1 and in full and broken lines in Fig. 3. Said bolt is engaged with the one of said wings which is at the bottom of its travel and in raising the same to open or close the gate through its geared connection with the bevel-pinion 11 co-incidentally effects the lowering of the opposite wing which may be similarly engaged upon the following upward movement of the lever 18 to effect the opposite movement of the gate.

The respective wings are vibrated in opposite vertical directions at each complete swinging movement of the gate and are alternately actuated during their upward movement while the opposite wing is descending to the lowermost relative position to be engaged upon the next upward movement of the lever 18.

As shown and described the gate is opened or closed through the power exerted by the weight 22 in descending from its uppermost position, indicated by dotted lines in Fig. 1, to that illustrated in full lines in the view. With the apparatus in the latter position, the bolt 26 has its bolt-end 29 or 29¹ in the slot 16 of the wing which is uppermost. With a pull exerted upon lines 23 or 24, the inner end of said power-lever 20, the link 19 and the lever 18 are lowered. Such downward movement of the lever 18 relative to the uppermost wing causes the respective inclined edge 26¹ of the bolt 26 to engage the wall of said slot 16 and effect the retraction from the latter of the bolt-end engaged, say 29¹, to a medial position between the two wings illustrated in Fig. 2. Further downward movement of the lever 18 brings said bolt-end 29¹ into engagement with the cam-face 17¹ of the uppermost wing which influences the bolt laterally into the oppositely positioned slot 16 of the low-

ermost wing. Then when the pull exerted upon said lines 23 or 24 is released, the weight begins to descend raising the lever 18 in its progress. The bolt-end 29 entered within said slot 16 raises the respective wing 70 which actuates the gate to open or close the same and at the same time causes the opposite wing to descend to where it may be engaged upon the next descending movement of lever 18.

The gate is provided with a latch that may be released before the open or closing movements of the gate are begun. Such latch and releasing mechanism therefor may be described as follows: The long arm 31 of the latch-bar is receivable in a notch of a bracket 32 upon an abutting gate-post 33 and also upon a post (not shown) at the termination of the gate's opening movements. Said latch-bar is pivoted at 34 and the short arm thereof upon the opposite side of said pivot is engaged by the arm of a bell-crank 35 whose other arm is connected with one end of a rod 36 whose opposite end is connected in similar fashion to a bell-crank 37.

38 indicates a releasing bar slidably mounted upon the gate and provided with a notch 39, and connected with the link 19 by a rigid rod 40. When the weight 22 is 95 elevated to actuate the gate the link 19 is forced downwardly coincidentally with the lever 18, the rod 40 forcing downwardly the bar 38 until the lateral arm 37¹ of the bell-crank 37 is engaged in notch 39. Upon 100 the first upward operative movement of the link 19 and lever 18 the releasing bar is influenced upwardly to oscillate said bell-crank 37 and the connected bell-crank 35 to release said latch-arm 31. In the upward 105 movement of lever 18 there is provided a small amount of lost motion before the movement is communicated to the respective wing 15. This may be accomplished by proportioning the length of the slot 16 relative to the respective end of the bolt 26 to allow of some movement of the latter before the wing is influenced.

It will be understood that the lines 23 and 24 are led to a suitable distance upon each side of the gate, respectively, to be grasped by the traveler in a vehicle before reaching the gate. He pulls upon the line to elevate the weight 22 whereupon the falling weight directly actuates the opening of the gate. 110 Upon passing through the gate the passenger similarly employs the other line to raise the weight 22 to close the gate after him.

The invention is simple in construction, is positive and reliable in operation, and is 125 extremely well-adapted for the purposes for which intended.

While I have described my invention with some detail, I do not intend to confine myself to the exact construction shown, as ob- 130

viously modifications of parts and changes in detail may be made within the scope of the claims without departing from the spirit of the invention or sacrificing its advantages.

What I claim as new and desire to secure by Letters Patent of the United States, is—

1. In gate-actuating mechanism, a bevel-pinion, a pair of bevel-gears in mesh upon opposite sides of said pinion, a wing rigidly connected with each said gear, a lever, a vibratile bolt pivotally mounted in said lever and adapted to make operative engagement alternately with said wings, and means to actuate said lever at a distance from the gate.

2. In gate-actuating mechanism, a bevel-pinion, a pair of bevel-gears in mesh upon opposite sides of said pinion, a wing rigidly connected with each said gear, said wings arranged to be at opposite ends of their travel when said gate is fully opened or closed, a lever, a vibratile bolt pivotally mounted in said lever and adapted to make operative engagement alternately with said wings, and means to actuate said levers at a distance from the gate.

3. In gate-actuating mechanism, a bevel-pinion, a pair of bevel-gears in mesh upon opposite sides of said pinion, a wing rigidly connected with each said gear, said wings arranged to be at opposite ends of their travel when said gate is fully opened or closed, a lever pivoted in the axis of said gears, a vibratile bolt pivotally mounted in said lever and adapted to make operative engagement alternately with said wings, and means to actuate said lever at a distance from the gate.

4. In gate-actuating mechanism, a bevel-pinion, a pair of bevel-gears in mesh upon opposite sides of said pinion, a wing rigidly connected with each said gear, a lever, a vibratile bolt mounted pivotally in said lever and adapted to make operative engagement alternately with said wings, a power-lever operatively connected with said lever and provided with a weight at one end, and lines extending to a distance at each side of said gate for actuating said power-lever.

5. In gate-actuating mechanism, a bevel-pinion, a pair of bevel-gears in mesh upon opposite sides of said pinion, a wing rigidly connected with each said gear, said wings arranged to be at opposite ends of their travel when said gate is fully opened or closed, a lever pivoted in the axis of said gears, a vibratile bolt pivotally mounted in said lever and adapted to make operative engagement alternately with said wings, a power-lever operatively connected with said lever and provided with a weight at one end, and lines extending to a distance at each side of said gate for actuating said power-lever.

6. In gate-actuating mechanism, a bevel-

pinion, a pair of bevel-gears in mesh upon opposite sides of said pinion, a wing rigidly connected with each said gear, a lever pivotally mounted in the axis of said gears, a vibratile bolt pivotally mounted in said lever and adapted to make operative engagement alternately with said wings, a power-lever operatively connected with said lever and provided with a weight at one end, and lines extending to a distance at each side of said gate for actuating said power-lever.

7. In gate-actuating mechanism, a bevel-pinion, a pair of bevel-gears in mesh upon opposite sides of said pinion, a wing rigidly connected with each said gear, said wings arranged to be at opposite ends of their travel when said gate is fully opened or closed, a lever, a vibratile bolt pivotally mounted in said lever and adapted to make operative engagement alternately with said wings, a power-lever operatively connected with said lever and provided with a weight at one end, and lines extending to a distance at each side of said gate for actuating said power-lever.

8. In a gate, actuating mechanism therefor comprising a bevel-pinion rigidly mounted in the swinging axis of said gate, a pair of bevel-gears in mesh upon opposite sides of said pinion and provided with engageable devices, a lever provided with means for operatively engaging said gears alternately to oscillate said pinion, and means operative at a distance from the gate for actuating said lever.

9. In a gate, actuating mechanism therefor comprising a bevel-pinion rigidly mounted in the swinging axes of said gate, a pair of bevel-gears in mesh upon opposite sides of said pinion and provided with engageable devices, a lever provided with means for operatively engaging said gears alternately to oscillate said pinion, a heavy body operatively connected with said lever, and means operative at a distance from the gate for raising said body to actuate said lever.

10. In a gate, actuating mechanism therefor comprising a bevel-pinion rigidly mounted in the swinging axis of said gate, a pair of bevel-gears in mesh upon opposite sides of said pinion and provided with engageable devices, a lever provided with means for operatively engaging said gears alternately to oscillate said pinion, means operable at a distance from the gate for actuating said lever, latch devices for retaining said gate in its open or closed condition, and means to release said latch before the gate is actuated.

11. In a gate, actuating mechanism therefor comprising a bevel-pinion rigidly mounted in the swinging axis of said gate, a pair of bevel-gears in mesh upon opposite sides of said pinion and provided with en-

2
gageable devices, a lever provided with means for operatively engaging said gears alternately to oscillate said pinion, a heavy body operatively connected with said lever, 5 means operative at a distance from the gate for raising said body to actuate said lever, latch devices for retaining said gate in its open or closed condition, and means to re-

lease said latch before the gate is actuated.

10 Signed at Irondale, Wash., this 27th day of November, 1912.

MICHAEL DILORENZO.
